(57) CLAIM

The Design for a handheld kitchen utensil to protect against accidental cuts, as shown and described.

DESCRIPTION

FIG. 1 is a front view of one form of the invention.
FIG. 2 is a right side view of the embodiment of FIG. 1. The left side view is a mirror image thereof.

FIG. 3 is a top view of the embodiment of FIG. 1.
FIG. 4 is a bottom view of the embodiment of FIG. 1.
FIG. 5 is a rear view of the embodiment of FIG. 1; and,
FIG. 6 is a perspective view of the embodiment of FIG. 1.
